UNITED STATES PATENT OFFICE.

SIDNEY D. SPENCE, OF LUDLOW GROVE, OHIO.

GRATE.

SPECIFICATION forming part of Letters Patent No. 278,191, dated May 22, 1883.

Application filed August 26, 1882. (No model.)

To all whom it may concern:

Be it known that I, SIDNEY D. SPENCE, of Ludlow Grove, in the county of Hamilton and State of Ohio, have invented a new and useful Improvement in Grates, which improvement is fully set forth in the following specification and accompanying drawings, in which—

Figure 1 is a front view of the improved grate. Fig. 2 is a side view of the same, partly in section. Fig. 3 is a central vertical transverse section; and Fig. 4 is a perspective view of the rear upper part of the improved grate, partly in section, with the hood.

The object of my invention is to provide a removable front and grate for the ordinary fire-place opening in a chimney, which front shall combine in itself a hood or covering for the fire-space, a grate, and a damper, all as will now be more fully set out and explained.

In the accompanying drawings, A represents the flue, and B a section of the ordinary mantel-front. My invention does not contemplate any change either in the mantel-front or in the flue.

25 Represents the hood, having a broad flange, D, around the arch and on the two vertical edges. This hood conforms in shape to the fire-place opening. The flange D should preferably be wide enough to provide for variations in the size of the fire-place opening. The lower half of the hood contains the fire-basket E. The fire-basket has at each end a hook, F, and the limbs G of the hood have on the inner sides lugs H, on which the hooks F rest when the fire-basket is in position. The fire-basket thus forms a continuation of the hood, and when attached to the fire-place fits snug and close to the limbs or sides G, while the bottom e of the fire-basket extending back to the wall 40 of the fire-place, the connection between the fire-basket and fire-place is now complete at all points, and the space between the fire basket or grate E e and the fire-place walls constitutes the ordinary fire-chamber. All of that space above the fire-basket is closed by the hood. Hence the air entering the combustion chamber must all enter through the fire-basket below the hood.

The hood C is provided with a fuel-door, I, and mica windows on the sides, if desired. 50 The upper part or arch of the hood is provided with a plate, J, to which a sheet-metal plate, K, is hinged. This plate K is preferably composed of wrought-iron, so it may be cut or trimmed to fit the ledge L at the throat of the 55 chimney. The object of the hinged plate K is to provide a damper for the fire-place, and the design of the plate J is to prevent the product of combustion from passing from the fire-place around the damper-plate K. 60

A rod, M, having a knob on its outer end, passes through the upper face of the hood C, and has its inner end hinged to the lid or plate K. The rod M is provided with a ratchet, N, on the under side, which acts against the hood 65 to hold the damper-plate in any desired position. It is obvious that a much better draft can be obtained by the use of this hood as a fire-front than without, and that by the use of the damper the heat can be regulated and consumption of coal utilized. 70

What I claim as new, and desire to secure by Letters Patent, is—

1. As an article of manufacture, an independent and detachable fire-place front, consisting of the hood C, having door I, the vertical limbs G, and the fire-basket E, having bottom extension, e, which front can be applied to my fire-place and thus constitute the ordinary fire and combustion chamber in the space 80 between them.

2. In an independent and removable fire-place front, made complete in itself, and without a back, the combination of the hood C, having door I, limbs G, the grate or fire-basket E e, damper K, and rod M, substantially as set forth. 85

In testimony that I claim the foregoing I have hereunto set my hand, this 9th day of August, 1882, in the presence of witnesses.

SIDNEY DEE SPENCE.
